UNITED STATES PATENT OFFICE

2,462,831

DETERGENTS AND METHOD OF MAKING
THEM

Emil E. Dreger, Summit, and John Ross, Ramsey, N. J., assignors to Colgate-Palmolive-Peet Company, Jersey City, N. J., a corporation of Delaware

No Drawing. Original application July 9, 1937, Serial No. 152,852. Divided and this application March 13, 1943, Serial No. 479,106

8 Claims. (Cl. 260—413)

1

This invention relates to a new process for producing materials adapted to function as wetting agents, detergents or the like, and to the materials themselves. More particularly, the invention relates to the utilization of short-chain fatty acids, which are not ordinarily satisfactory for the preparation of detergents, wetting agents and the like, in the production of materials which will function efficiently for these purposes, and to the production of a soap product substantially free of the soaps of such short-chain fatty acids.

A common type of soap is made from a blended mixture of animal fats, such as tallow, and fatty oils of vegetable origin. The fatty oils that are commonly used in the production of detergent materials almost invariably contain appreciable percentages of fatty acid esters (glycerides), the fatty acids of which contain less than twelve carbon atoms. We have recognized that the sodium salts of these fatty acids are of little or no value and, if they are left in the mixture along with the salts of the higher fatty acids, the result is simply a corresponding amount of inactive or inefficient material in the final soap product. In accordance with the present invention, the lower fatty acids are removed from the fatty oils containing these low molecular weight components to make the final soap product more effective. The particular fractionating method employed to effect the separation of the fatty acids into a low molecular weight fraction and a higher molecular weight fraction is not a part of the present invention, and any satisfactory method may be employed.

The removal of such fatty acids reduces the quantity of the final detergent product that can be produced from a given amount of fatty oil, and yields, as a by-product, considerable quantities of these lower fatty acids. For example, about 21% of the fatty acids in coconut oil contains less than twelve carbon atoms, and about 13% of the fatty acids in palm kernel oil also contains less than twelve carbon atoms.

According to the present invention, both the light and the heavy fractions of the fatty acids derived from the fatty oils, i. e., the light fraction containing less than twelve carbon atoms and the heavy fraction containing at least twelve carbon atoms, are utilized for the preparation of detergents and the like, although the material having fatty acid radicals containing less than twelve carbon atoms is treated differently from the material containing fatty acid radicals having more than twelve carbon atoms.

The lower fatty acids of a molecular weight

2

less than that of lauric acid, i. e., those containing less than twelve carbon atoms, are caused to react to form useful efficient detergents in the manner fully described in our prior co-pending application Serial No. 152,852, filed July 9, 1937, now Patent No. 2,321,020, granted June 8, 1943, of which the present application is a division.

The higher fatty acids in the heavier fraction, which include those fatty acids of the molecular weight of lauric acid or greater, i. e., fatty acids containing at least twelve carbon atoms, are used for making soap. The particular soap making method forms no part of the present invention, and any suitable process may be employed, e. g., the fatty material forming the residue of the fatty oils upon removal therefrom of the fatty acids having less than twelve carbon atoms may be reacted with an alkali to produce the soaps, e. g., sodium soaps, of the higher fatty acids. It will be apparent to those skilled in the art that the new soap product contains the soaps of fatty acids having at least twelve carbon atoms and is substantially free of the soaps of fatty acids having less than twelve carbon atoms. At least a portion of the soap product consists of soaps of the fatty material forming the residue of the fatty oils upon removal therefrom of fatty acids having less than twelve carbon atoms, including the fatty acids derived from the glycerides in such oil having fatty acid radicals of less than twelve carbon atoms. These fatty oils include those which are commonly used in the production of detergent materials, such as coconut oil, palm kernel oil, etc.

The present invention is not to be restricted to any specific proportions or manner of procedure beyond the limitation of the appended claims.

We claim:

- 40 1. A non-irritative soap product containing the soaps of fatty acids having at least 12 carbon atoms and substantially free of the soaps of fatty acids having less than 12 carbon atoms, at least a portion of said soap product consisting of soaps
- 45 of the fatty material forming the residue of fatty oil containing an appreciable percentage of glycerides having fatty acid radicals of less than 12 carbon atoms upon removal therefrom of fatty acids having less than 12 carbon atoms, including the fatty acids derived from the glycerides in said oil having fatty acid radicals of less than 12 carbon atoms, said soaps having at least as good lathering properties as those which characterize the soaps of the fatty acids of the said fatty oils and being free from the skin irritating properties

normally characterizing said soaps of said fatty oils.

2. A non-irritative soap product containing the soaps of fatty acids having at least 12 carbon atoms and substantially free of the soaps of fatty acids having less than 12 carbon atoms, at least a portion of said soap product consisting of soap of the fatty material forming the residue of cocoanut oil upon removal therefrom of fatty acids, including the fatty acids derived from the glycerides in said oil having fatty acid radicals of less than 12 carbon atoms, said soap having at least as good lathering properties as those which characterize the soaps of the fatty acids of cocoanut oil and being free of the skin-irritating properties which characterize soaps of cocoanut oil.

3. A non-irritative soap product containing the soaps of fatty acids having at least 12 carbon atoms and substantially free of the soaps of fatty acids having less than 12 carbon atoms, at least a portion of said soap product consisting of soaps of the fatty material forming the residue of palm kernel oil upon removal therefrom of fatty acids, including the fatty acids derived from the glycerides in said oil having fatty acid radicals of less than 12 carbon atoms, said soap having at least as good lathering properties as those which characterize the soaps of the fatty acids of palm kernel oil and being free of the skin-irritating properties which characterize the soaps of palm kernel oil.

4. In the process for making mild soap free from skin irritating properties from fatty oils containing low molecular weight components having skin irritating properties and higher molecular weight components free from skin irritating properties, the steps of fractionating the fatty acids of said fatty oils to remove a fraction containing fatty acids having less than 12 carbon atoms while retaining a fraction containing the fatty acids having at least 12 carbon atoms and making soap from the latter fatty acid fraction.

5. In the process for making a mild soap comprising the soaps of cocoanut oil fatty acids, said soap having good sudsing characteristics and freedom from skin irritating properties, the steps

of fractionating cocoanut oil acids to remove a fraction containing fatty acids of a molecular weight less than the molecular weight of lauric acid while retaining a fraction comprising the fatty acids of a molecular weight of lauric acid or greater, and reacting the latter fraction with an alkali to produce the soaps of the fatty acids thereof.

6. In the process for making a mild soap comprising the soaps of palm kernel oil fatty acids, said soap having good sudsing characteristics and freedom from skin irritating properties, the steps of fractionating palm kernel oil acids to remove a fraction having a molecular weight of less than the molecular weight of lauric acid while retaining a fraction comprising the fatty acids of a molecular weight of lauric acid or greater, and reacting the latter fraction with an alkali to produce the soaps of the fatty acids thereof.

7. A detergent product comprising soaps of the fatty material forming the residue of oils containing an appreciable percentage of lower fatty acid esters, the fatty acids of which contain less than 12 carbon atoms, upon removal of said lower fatty acids.

8. The method of making a detergent from fatty oils containing an appreciable percentage of lower fatty acid esters, the fatty acids of which contain less than 12 carbon atoms, which comprises removing these lower fatty acids and making sodium salts of the higher fatty acids containing at least 12 carbon atoms.
